OPENING DEVICE FOR CARTONS

George W. Mai, St. Louis, Mo., assignor to Gaylord Container Corporation, St. Louis, Mo., a corporation of Maryland

Application January 10, 1951, Serial No. 205,332

1 Claim. (Cl. 229—51)

1
This invention relates to opening means for cartons, and more particularly of the class designed for packaging ice cream, foods, and the like.

Cartons of the class described are usually made from a blank scored to define side wall panels with marginal die cut end closure flaps and a sealing flap depending from the free outer margin of one of the panels, said sealing flap being glued flatwise to the outer face of the adjacent marginal portion of an upstanding wall panel. The free outer marginal portion of the sealing flap is free of glue so as to provide an unsecured grasping portion or tear tab which is torn thereby breaking the glue joint to open the carton. One of the principal objections to many of the conventional sealing flaps of ice cream and other food cartons arises from the frequent occurrence of tearing or peeling of the inner surface of the flap from the inner longitudinal edge of the glued portion into the wall panel in contact with the contents. This peeling often results in slivers torn from the liner or facing ply of the paperboard which contaminate the contents of the package.

One of the principal objects of the present invention is to provide a device for cleanly detaching the glued sealing flap of folding cartons from the underlying wall to which it is attached without peeling portions of the surface of the paperboard in contact with the contents of the carton.

Another object of the invention is to provide a glued flap for closing a carton which will securely seal the package against any accidental or premature opening and which may be readily released from the glue bond without contaminating the contents of the package.

The invention provides means for readily and cleanly detaching a carton sealing flap connected to a free edge of one panel thereof, said sealing flap being attached to the margin of an adjacent wall panel by a longitudinal strip of glue of less width than the sealing flap, said strip of glue being positioned between the outer free edge of said sealing flap and a discontinuous series of slits therein, said means comprising a longitudinal series of slits positioned between the glue strip and the inner longitudinal edge of the sealing flap, said slits being formed of perforations extending through the liner ply of the inner face of said sealing flap with the opposite ends of adjacent slits in substantially perpendicular alignment with said longitudinal series of slits.

In a preferred embodiment, the slits extend

2
substantially parallel to and are positioned between the glue strip and the score about which the flap is folded. This provides a line along which any tearing of the liner is arrested when breaking the glue joint to open the carton. The shape and size of the perforations may be varied and still come within the scope of the invention. In a preferred form of the invention the slits comprise two adjacent rows of relatively short evenly spaced slits substantially parallel to the fold line of the sealing flap, the slits of the respective rows being in staggered overlapping relation. In other forms of the invention, the perforations may take the form of a row of Z-shaped slits, or a row of straight slits and a row of slits disposed at an angle to the straight slits adjacent to and parallel to the first mentioned row, or they may comprise a row of diagonal slits.

Regardless of the shape of the perforations 20 the opposite ends of each staggered adjacent slit are in substantially perpendicular alignment with the fold line of the sealing flap to provide the severed portions of the liner the equivalent of a continuous straight line cut therethrough 25 when the seal is broken by an outward and slightly upward pull on the tear tab beginning at one end of the line of slits. The carton may also be opened by lifting upwardly at the center of the tear tab. With this method of opening the tear tab is not detached. Preferably, the ends of each 30 slit slightly overlap the opposite ends of each adjacent staggered slit along a line perpendicular to the fold line of the sealing flap to insure an invariable clean tear of the liner along the line of perforation. Each end edge of the sealing flap should be completely severed by one of the bottom slits as illustrated in Figures 3 through 6.

The slits are preferably made from the outer or exposed face of the sealing flap, since the slits may be cut simultaneously in one operation with the scoring and die cutting of the carton blank. Obviously, if desired they may be cut from the underface of the blank, but this usually involves a separate operation.

The invention consists in the parts and in the arrangements and combinations of parts herein-after described and claimed. In the accompanying drawings which form part of this specification and wherein like numerals refer to like parts wherever they occur:

Fig. 1 is a plan view of a blank for a carton embodying this invention,

Fig. 2 is a perspective view of the carton folded from the blank shown in Fig. 1 with a portion of the tear tab severed,

Figs. 3, 4, 5 and 6 are enlarged illustrations of several of the modified forms of the perforations of the invention.

Referring now to Figs. 1, 2 and 3 of the drawings in detail, it will be seen that the embodiment of the invention which is illustrated has been applied to a standard one-piece ice cream carton. The blank is shown in Figure 1 wherein a cover panel 1, a side or rear wall panel 2, a bottom panel 3, and a side or front wall panel 4 are defined by scores 5, 6, 7, 8 and 9 and are provided with end flaps 10, 11, 12 and 13 attached to the ends of wall panels 1, 2, 3, and 4, respectively. The cover panel 1 is provided with a sealing flap 14 defined by the score 6. A strip of glue 15 is applied to the underface of the sealing flap 14 which in the erected position of the carton lies flatwise against front wall panel 4. The outer or free edge of the sealing flap 14 provides a sealing tear tab 16 which lies flatwise against the front wall panel 4 in the assembled position of the carton. Two parallel lines of perforations or slits 17 are substantially parallel to the free edge of the tear or peeling tab 16 and are near the score 6 along which the sealing flap 14 is folded to a position flatwise against the front wall panel 4.

One way of assembling the carton comprises folding the bottom panel end flaps 12, the front panel 4, and the rear panel 2 upwardly from the bottom panel 3, folding the front and rear wall end flaps 13 and 11 inwardly and fastening them to each other, folding the cover panel end flaps 10 inwardly toward the box formed so that the lower edges of said end flaps 10 are positioned directly over the spaces between the upstanding bottom panel end flaps 12 and the joined front and rear wall end flaps 13 and 11, folding the cover panel 1 downwardly, applying an adhesive to form a glue strip 15, and folding the sealing flap 14 downwardly against the upper portion of the front wall panel 4. In a manufacturer's variation of the assembly of the carton the tear tab 16 is secured first to the wall panel 4 whereupon the carton is shipped in flatwise condition. To open the carton the front and rear wall end flaps 13 and 11 are disengaged and the tear tab 16 is grasped near one end thereof and pulled outwardly until the glue bond is broken, whereupon all portions of the carton may be readily opened and folded back into the plane of the bottom panel, thereby exposing the contents. The carton may also be opened by lifting upwardly at the center of the tear tab 16. With this method of opening the tear tab 16 is not detached.

The parallel lines of perforations are spaced apart a sufficient distance to avoid the accidental breaking of the sealing flap 14 by twisting but are sufficiently close to insure an easy release of the sealing flap 14. With this arrangement the liner on the underface of the flap 14 does not tear at the extremities of the lower line of perforations and any tendency to tear is promptly arrested by the upper perforations, the ends of which slightly overlap the opposite ends of the lower perforations. Consequently, the liner on the inner face of the sealing flap 14 is completely severed by the staggered double row of perforations and any tendency to tear beyond the upper line of perforations is completely arrested.

Any tearing of the outer ply of the sealing flap 14 is arrested in a similar manner by each of the forms of perforations illustrated in Figures 4, 5 and 6.

5 In the embodiment described the distance between the two parallel lines of slits may be varied. Generally, the greater the thickness of the material the closer the rows of slits may be placed together. The space between the two rows is varied so as to allow for constant ease of opening for all grades of material.

10 It is to be understood that the embodiments herein described are illustrative and not restrictive, and it is also to be understood that the invention may be susceptible of embodiment in other modified forms, and that all such modifications which are similar or equivalent hereto come equally within the scope of the claim next appearing.

20 What I claim is:

A carton comprising foldably, integrally connected bottom, side and top walls, the top and bottom walls having foldably connected, integral end flaps disposed right angularly inwardly in overlapping relation to form carton end walls, the side walls each having foldably, integrally connected end locking tabs disposed in releasably locked relationship and positioned against the outer face of the end flaps, the top wall having an integral sealing flap foldably connected to the front side margin thereof and disposed downwardly, flatwise against the upper portion of the outer face of the adjacent side wall, the sealing flap being secured to the adjacent side wall only by a longitudinal glue strip of substantially less width than the sealing flap and positioned parallel to and spaced considerably inwardly from its free outer side edge thus leaving a free unsecured longitudinally extending marginal portion of the sealing flap, means for arresting tearing and peeling of the exposed liner ply on the underface of the sealing flap when the glue bond between the sealing flap and the adjacent side wall is broken, said means comprising a row of closely spaced together, overlapping slits severing the exposed liner ply on the underface of the sealing flap, the row of slits being positioned closely adjacent and substantially parallel to the longitudinal glue strip, unsecured to the adjacent side wall, and spaced outwardly from the foldable connection between the glue strip and the top wall, whereby the said marginal portion of the sealing flap may be readily gripped with the fingers to enable the same to be pulled free from the adjacent side wall.
